UNITED STATES PATENT OFFICE.

GEORGE T. WARREN, SR., OF CHARLESTON, SOUTH CAROLINA.

LADDER.

1,154,147.

Specification of Letters Patent. Patented Sept. 21, 1915.

Application filed May 7, 1915. Serial No. 26,446.

To all whom it may concern:

Be it known that I, GEORGE T. WARREN, Sr., a citizen of the United States, residing at Charleston, in the county of Charleston 5 and State of South Carolina, have invented certain new and useful Improvements in Ladders, of which the following is a specification.

This invention relates to step ladders of 10 the propped type, and has for its object to provide improved means for bracing and connecting the sections of the ladder, to provide a firm and rigid structure, and one which can be easily manipulated in the use 15 of the ladder.

A further object is to provide improved means for supporting or holding a pivoted shelf in folded position.

In the accompanying drawing Figure 1 20 is a perspective view of the ladder. Fig. 2 is a horizontal section thereof, showing the brace in plan. Fig. 3 is a vertical section showing the manner of supporting the shelf when the ladder is folded.

Referring specifically to the drawing, 6 indicates the steps and 7 the stiles of the main section of the ladder, which may be constructed in any suitable or desired manner. The rear props or legs 8 are hinged at 30 9 to the top of the stiles.

For connecting the ladder and the props I provide a folding brace which comprises two links 10 pivoted at 11 to the inner faces of the stiles, and pivoted at 12 to the side 35 bars 13 of a U shaped frame or bar; said side bars being connected by a cross bar 14, the links being located on the outer sides of said bars 13. Each of said bars is also provided with a curved or hooked flange 15 which 40 form stops for the links 10, by engaging and embracing the same when the brace is unfolded or straightened. The ends of the U shaped brace are pivoted at 16 to the props 8, and the props are also connected and 45 strengthened by a cross brace 17 the ends of which are fastened to the props by the pivot bolts 16. The props are also braced and strengthened by a lower cross bar 18,

a cross rod 19 and two angular bars 20, which are set against the cross bar 18 at 50 their lower ends and are held by the cross bar 19 at their upper ends.

The folding shelf 21 is pivoted between the props by a cross rod 22, and this shelf has legs 23 which, when the ladder is set up, 55 engage under the top step 6 to hold the shelf in horizontal position. When the ladder is folded the shelf 21 swings up between the props, as shown in Fig. 3, and the cross bar 14 of the brace engages the depending 60 legs 23 and holds the shelf in upright or folded position between the props.

The manner of constructing the brace, with the U shaped bar, enables the brace to be readily folded or straightened, as the 65 cross piece 14 can be grasped to "break" or fold the brace, or to straighten the same. Furthermore, this cross bar gives a desirable rigidity to the brace, and enables both sides thereof to be manipulated or folded 70 simultaneously, and by one hand. When the brace is straightened the cross bar extends between the opposite sides or members thereof, and holds said members in proper position.

By the construction described a strong and durable step ladder is produced, and one capable of being readily folded or unfolded when in use. And when the ladder is folded the U shaped brace rests firmly 80 and closely between the props 8, which protect the same.

I claim:

The combination with a ladder, and props hinged thereto, of a shelf pivoted between 85 the props, and a folding brace connecting the ladder and props, one member of the brace having a cross bar arranged to strike the lower end of the shelf and hold the same upright when in folded position. 90

In testimony whereof, I affix my signature in presence of two witnesses.

GEORGE T. WARREN, Sr.

Witnesses:

W. M. B. PARSONS,
C. F. LUNZ.
